UNITED STATES PATENT OFFICE.

WALTER A. DORSEY, OF COLUMBUS, OHIO, ASSIGNOR TO THE BONNEY-FLOYD COMPANY,
OF COLUMBUS, OHIO, A CORPORATION OF OHIO.

CAR-MOVER.

1,272,398.

Specification of Letters Patent. Patented July 16, 1918.

Application filed May 18, 1914, Serial No. 839,417. Renewed December 12, 1917. Serial No. 206,854.

To all whom it may concern:

Be it known that I, WALTER A. DORSEY, a citizen of the United States, residing at Columbus, in the county of Franklin and

5 State of Ohio, have invented certain new and useful Improvements in Car-Movers, of which the following is a specification, reference being had therein to the accompanying drawing.

10 The invention relates especially to car movers of the class in which each has two car wheel engaging elements and the principal object of the invention is to provide in a car mover of this class improved means 15 for moving one of these elements with respect to the other and with respect to the rail. A further object is to provide an improved means for mounting and guiding the movable elements above referred to. A still 20 further object is to provide an improved fulcrum for engaging the rail. Other objects will be apparent from the following specification and claims.

Of the drawings which represent the preferred embodiment of the invention—

25 Figure 1 is a side view partly in section showing a car mover embodying my invention in use.

Fig. 2 is a view similar to Fig. 1 showing 30 the car mover in a different position.

Fig. 3 is a plan view.

Fig. 4 is a fragmentary sectional view taken on an enlarged scale along the line 4—4 of Fig. 2.

35 Referring to the drawings 1 represents a track rail and 2 a wheel of a car to be moved along the track.

3 is a pinch bar having the head 4 which is provided with a curved surface 5 adapted 40 to engage the surface of the car wheel.

Formed integrally with the head 4 are two parallel rearward extending arms 6—6. The pinch bar is provided intermediate its ends with a transverse fulcrum piece 7 45 which is set into a suitably shaped transverse slot in the rear part of the head. The fulcrum piece 7 is provided with a sharp corner which projects downward from the slot to engage the track rail, and prefer-

50 ably the fulcrum is square in cross section and fits into a square slot in the head. Near the center the fulcrum piece is turned to be circular in cross section, as clearly indicated at 8 in Fig. 4. This construction provides two rail engaging points near the

edges of the rail, thus providing a firm grip on the rail which is frequently so worn as to have a rounded upper surface, as indicated in Fig. 4.

Formed in the upper part of the head 4 is a recess 9 which is bounded at its sides by the forward parts of the two arms 6—6. This recess is provided with a smoothly curved forward surface forming a pivotal socket for the forward sharply curved end 65 of a thrust lever 10. This lever 10 has a flat upper surface 11 adapted to be forced against the surface of the wheel 2. The lever 10 has an arcuate slot 12 concentric with the pivotal axis at the front end of the 70 lever. Through this slot there extends a transverse retaining pin 13 mounted at its ends in ears formed on the arms 6—6.

Pivotedly connected between the rear ends 75 of the arms 6—6 by means of the pivot bolt 14 is an operating lever 15. This lever is formed of metal at its lower forward part, but the rear upper part preferably, though not necessarily, is formed of wood. The forward lower end of the lever 15 is provided with the curved surface 16 adapted to engage the downward convexed surface 17 on the thrust lever 10. When the lever 15 is swung relatively to the pinch bar about the axis at 14 the surface 16 will engage the 80 surface 17 with a substantially rolling contact and force the thrust lever 10 upward about the axis at its forward end. The upward movement of the thrust lever 10 and of the forward end of the lever 15 is limited by the engagement of the retaining pin 13 with the lower end of the slot 12.

90 Preferably for the sake of lightness the forward part of the lever 15 is formed with a central vertical web 15^a and a top flange 15^b projecting on both sides from the central web 15^a. For engaging the track there is provided a small supplemental web 15^c at the extreme forward end of the lever. Formed on the arms 6—6 are inward projecting lugs 6^a—6^a which engage the flange 15^b and thus limit the movement of the forward end of the lever 15 downward with respect to the pinch bar.

95 From the foregoing description the operation of my improved car mover will be readily understood. The operator first places the car mover in position, as indicated in Fig. 1, with the surfaces 5 and 11 100 engaging the car wheel, the thrust lever 10 110

being in its lower position as indicated. The sharp corners of the fulcrum piece 7 engage the track and prevent the device from moving therewith. The operator 5 then pushes down at the rear outer end of the lever 15. The pressure on the operating lever is transmitted to the thrust lever to push it upward and thus force the wheel forward. It will be noted that at starting 10 the point of contact between the surfaces 16 and 17 is relatively near the axis at 14 and relatively remote from the fulcrum of lever 10, thus giving the operator a relatively powerful leverage. The effective leverage 15 decreases as the rear end of the hand lever 15 is pushed downward, because of the rolling contact between surfaces 16 and 17, but this decrease does not come until the wheel has been started and less force is required. 20 By reason of this construction the amount of force which is applied is approximately proportioned to the amount of force required.

The downward movement of the lever 25 necessarily causes a powerful down thrust on the pivot bolt 14. Use is made of this down thrust as it is transmitted to force the front end of the pinch bar upward against the wheel surface. In this way an extremely powerful compound action upon 30 the wheel is secured.

Even after the push lever 10 has reached the extreme limit of its movement the downward movement of the lever 15 can be 35 continued, the forward end of the head 4 still being available for moving the wheel. It will be observed that the wheel contacting surface 5 is curved so as to provide a substantially rolling contact with the wheel 40 surface.

As to the details of form and mounting of the thrust lever 10 there can be considerable variation, but the construction which I have shown has many advantages. The 45 provision of direct pivotal contact between the thrust lever and the pinch bar not only enables the device to be cheaply manufactured but also makes it much stronger than it would be if use were made of a separate 50 pivot pin which might be readily sheared or

broken. The retaining pin 13 serves as a convenient means for holding the thrust lever in place and also for limiting its movement.

The fulcrum piece which I provide is of 55 superior construction as it has two separate points of contact with the rail surface. On this account it has a much firmer grip than do those fulcrum pieces of earlier devices which had only a single straight rail engaging corner. 60

What I claim is:

1. In a car mover, the combination with the pinch bar adapted to be fulcrumed on the rail and formed with an open pivot 65 socket in front of its fulcrum, and the operating lever pivoted to the rear end of the pinch bar and having an arm projecting forward of its pivot, of the thrust lever having its forward and lower end loosely 70 and detachably pivoted in the said socket in the pinch bar, and a bracing holder securing the rear end of the thrust lever to the pinch bar with limited looseness whereby the rear end of the thrust lever is laterally braced but can be bodily moved by the operating lever while the front end rocks loosely in said socket. 75

2. In a car mover, the combination of a pinch bar adapted at its forward end to engage a car wheel and provided between its ends with a rail engaging fulcrum and with a socket, a wheel engaging thrust lever having its forward end seated in the socket the walls of which form a pivotal abutment, 85 the said lever having a transverse slot concentric with the pivotal axis, a pin mounted on the pinch bar and extending through the slot for holding the thrust lever in place without preventing upward and downward 90 movement, and an operating lever pivoted to the pinch bar and adapted to move the thrust lever about its forward pivotal axis. 90

In testimony whereof, I affix my signature in presence of two witnesses.

WALTER A. DORSEY.
